UNITED STATES PATENT OFFICE.

CHARLES FRED SNOVER, OF SAGINAW, MICHIGAN.

CHICKEN-BROODER.

No. 835,871.

Specification of Letters Patent.

Patented Nov. 13, 1906.

Application filed April 27, 1905. Serial No. 257,628.

To all whom it may concern:

Be it known that I, CHARLES FRED SNOVER, a citizen of the United States, residing at Saginaw, in the county of Saginaw and 5 State of Michigan, have invented certain new and useful Improvements in Chicken-Brooders; and I do hereby declare the following to be a full, clear, and exact description of the invention, such as will enable others skilled 10 in the art to which it appertains to make and use the same.

This is a chicken-brooder; and the improvements consist in certain constructions and arrangements and the equivalents thereof 15 whereby I attain the objects of my invention.

These objects are, first, to produce a chicken-brooder that will impart a mild and uniform heat to all parts of the brood-chamber, to efficiently ventilate the chamber, and to provide a hover-cloth that will not only inclose the chicks, but will also serve as a flexible cover under which they may creep, the hover-cloth being of such form that it will 25 rest upon the backs of the chicks, it being found in practice that chicks are quieter and less subject to nervousness when they are protected by a flexible warm covering that presses lightly down upon their backs.

With these and certain other objects in view, which will be further explained in the specification, my invention consists in the devices illustrated in the accompanying drawings, in which—

Figure 1 is a perspective sectional elevation, broken away in parts, showing the improvements. Fig. 2 is a sectional detail of the air-heating chamber. Fig. 3 is a perspective view of the sliding lamp-rest. Fig.

4 is an enlarged sectional detail through the air-heating chamber. Fig. 5 is a vertical section taken through the brooder; and Fig. 6 is a detail view, broken away, of the pivoted arm 5a.

As is clearly shown in the drawings, the device consists in the usual lamp-compartment 1, above which is a compartment 2, containing the air-heating chamber, and above the compartment 2 is the brood-chamber 3.

The bottom of the lamp-chamber is provided with a sliding lamp-support 1a, having a window 1b in its upright end, and an oblique mirror 1c, arranged below the window, by which the condition of the lamp-flame can

be inspected from without the brooder without withdrawing the lamp.

To produce an even and mild heat and to properly ventilate the brood-chamber 3, I provide in the heating-compartment 2 an air-heating device. (Illustrated in detail in Figs. 2 and 4.) The office of this air-heating device is to deliver into the hover above fresh warm air required for the chicks. Its construction is as follows:

3a is the wooden floor of the brood-chamber 3, and the floor has an opening located centrally of the chamber to receive the warm-air stack 4a of the air-heater. Beneath the floor 3a and between it and the top 4b of the air-heating chamber 4 is inserted a sheet of asbestos 3b to prevent overheating the floor. The bottom of the chamber 4 is higher in the middle than at the circumference, forming an annular space 4e around the central portion. Into this annular space extends two or more air-supply pipes 4c, communicating with the outside air. The lamp 1d is placed beneath the center of the chamber 4, and a baffle-plate 4d is provided just above the lamp-chimney to prevent overheating the central part of the bottom of the chamber to diffuse the heat. Air taken through the pipes 4c flows over the raised bottom of the chamber and passes up through the stack 4a into the brood-chamber 3.

The hover, which is removable, is located in the chamber 3. It consists in a cover-plate 5, secured to a pivoted arm 5a, and occupies the center of the chamber 3. The cover-plate 5, which is secured to and carried by the pivoted arm 5a, is supported in position by reason of the fact that the reticulated bottom 6b of the diffusion-chamber 6 rests upon the cylindrical guard 10, hereinafter referred to. To the under side of the cover 5 is secured a diffusion-chamber 6, the object of which is to diffuse the warm air received from the stack 4a and to permit it to gradually filter down through the screened bottom of chamber 6 to the brood-space beneath. The bottom of chamber 6 is preferably formed of fine-wire mesh or coarse fabric 6b, through which the air is filtered, and it is provided with a suitable moisture-cup 6a, the diaphragm 6b being made removable in any suitable manner.

With this device no draft can strike the chicks, for all air passing from the warm-air

pipe 4^a to the brood-chamber must pass through the diaphragm 6^b, forming the bottom of chamber 6, and is thereby slowly filtered and uniformly distributed throughout 5 the area of the brood-chamber.

15 Around the periphery of the cover 5 is suspended a curtain 7, and inclosed by the curtain is the hover-cloth 8, which is bag-shaped in section, as shown in Figs. 1 and 5, and 10 forms an annular ring suspended from the cover 5. The object in making the hover-cloth circular, as shown, is for the purpose of affording plenty of room for the chicks. It is well known that in brooders heretofore 15 used the chicks will crowd together beneath the hover for warmth, the stronger chicks burrowing or piling under the weaker chicks until finally the lower or bottommost chicks are smothered by those above. This is particularly so when a bag-shaped hover is provided, and I avoid this disadvantage by 20 making my hover annular, so that the chicks will gather in a ring beneath instead of in a pile.

25 An automatic thermostat 8^a of any suitable construction is provided inside the hover-cloth 8 to open and close the air-vent 9, communicating with the brood area 6, so that the surplus of hot air may be discharged 30 from the brood area.

To prevent the chicks from hovering too close to the pipe 4^a and being thereby injured by crowding, I provide a cylindrical guard 10 around the pipe 4^a, as shown in Fig. 4.

35 This guard may be formed in whole or in part of reticulated or other suitable material.

When it is desired to examine the chicks, the entire brood area may be uncovered by 40 raising the cover 5 by means of the pivoted arm 5^a. The brood-chamber 3 and the exercise and feeding chamber C may be provided with windows D D or other suitable means to permit the inspection and ventilation of the chambers.

45 A thermometer X is preferably carried by the cover 5, the thermometer passing through the cover between the hover 8 and the cylindrical guard 10, the upper end of the thermometer projecting above the cover to permit it to be inspected.

To carry off the lamp-fumes from chamber 1, I provide a flue 1^e, connecting the chamber with the outside air, whereby the heat of the fumes is used to warm the exercise and feeding chamber C.

55 By the means above described I have produced a brooder simple in construction, easy to clean and inspect, and so arranged that uneven heating or overheating of the brood-chamber is avoided and constant circulation of warm fresh air therethrough is maintained. It will be observed that the fumes from the lamp cannot gain access to the brood-chamber and that the brood-chamber is so ar-

ranged that the hover incloses a free space 65 wherein the chicks may gather.

What I claim as my invention, and desire to secure by Letters Patent, is as follows:

1. In a brooder, the combination with a lamp-chamber, a brood-chamber, an annular dead-air chamber interposed between the lamp and brood chambers, an air-heating chamber surrounded by the dead-air chamber, pipes leading through the dead-air chamber, to supply fresh air to the air-heating chamber, a dome projecting into the air-heating chamber from the lamp-chamber to form an annular passage in the air-heating chamber, with which passage the pipes communicate, a stack projecting from the air-heating chamber, into the brood-chamber, a perforated guard surrounding the stack, a hover surrounding the guard, the hover comprising a pivotally-supported cover, a diffusion-chamber carried thereby and receiving the upper end of the stack, the diffusion-chamber provided with a removable reticulated bottom, an annular bag-like hover depending from the cover, and surrounding the diffusion-chamber to leave a clear space therebeneath, 90 an air-moistening means carried by the diffusion-chamber, an air-outlet means located between the diffusion-chamber and the bag-like hover, and automatic means controlling said outlet.

2. The combination in a brooder, with a brood-chamber, and a lamp-chamber, of a dead-air chamber, interposed between the two, an air-heating chamber surrounded by the dead-air chamber, and having an annular channel, pipes leading across the dead-air chamber for conducting fresh air to the air-heating chamber, and means for conveying the fresh heated air to the brood-chamber.

3. In a brooder, the combination with a lamp-chamber and a brood-chamber, of a dead-air chamber interposed therebetween, an air-heating chamber surrounded by the dead-air chamber, means for conveying fresh air across the dead-air chamber to the air-heating chamber, a dome projecting from the lamp-chamber into the air-heating chamber beneath the brooder-chamber and means for conveying the heated air to the brood-chamber.

4. In a brooder, the combination with a brood-chamber, of an air-heating chamber, a stack projecting into the brood-chamber from the air-heating chamber, a stationary perforated guard surrounding the stack and a hover removably surrounding the guard.

5. In a brooder, the combination with an air-heating chamber, a brood-chamber, and means for conveying the warm air from the air-heating chamber into the brood-chamber, 125 of a hover and an arm pivotally secured at one end to the wall of the brood-chamber, the opposite end of the arm carrying the hover.

6. In a brooder, the combination with a brood-chamber and means for heating the same, of a stack conveying the warm air into the brood-chamber, a hover surrounding the stack, said hover comprising an elevated diffusion-chamber into which the stack discharges, a diffusion means removably carried by and forming the bottom of the diffusion-chamber, and an annular bag-shaped 5 hover member, surrounding the diffusion-chamber and lying outside thereof to leave a free unobstructed space beneath the diffusion-chamber and surrounded by the bag-shaped hover.
- 15 7. In a brooder, the combination with a brood-chamber and a stack for conveying fresh warm air thereto, of a diffusion-chamber located above the floor of the brooder-chamber into which the stack discharges, a 20 removable diffusion member forming the bottom of the diffusion-chamber, a bag-shaped hover member surrounding the periphery of the diffusion-chamber to leave a free unobstructed space therebeneath, wherein the 25 warm air is discharged, and allowed to pass out beneath the hover member and an air- moistening means located within the diffusion-chamber.
8. In a brooder, the combination with a brood-chamber and a stack for conveying 30 fresh warm air thereto, of a diffusion-chamber located above the floor of the brooder-chamber into which the stack discharges, a removable diffusion member forming the bottom of the diffusion-chamber, a bag-shaped 35 hover member surrounding the periphery of the diffusion-chamber to leave a free unobstructed space therebeneath wherein the warm air is discharged and allowed to pass out beneath the hover member, an air-discharge means located outside the diffusion-chamber and between the latter and the hover member, and means for controlling the discharge of warm air from the space surrounded by the hover member. 40
- 45 In testimony whereof I affix my signature in presence of two witnesses.
